Primary Examiner — Michelle E. Wilson*Assistant Examiner* — Tracey J Bell(57) **CLAIM**

The ornamental design for a bracelet, as shown and described.

DESCRIPTION

FIG. 1 is a top front side perspective view of a bracelet showing my new design;

FIG. 2 is a top view of the bracelet;

FIG. 3 is a bottom view of the bracelet;

FIG. 4 is a left side view of the bracelet, a right side view being a mirror image thereof;

FIG. 5 is a front view of the bracelet; and,

FIG. 6 is a rear view of the bracelet.

The broken lines in the drawing figures illustrate surface features or indicia forming no part of the claimed design.

1 Claim, 5 Drawing Sheets(56)
